UNITED STATES PATENT OFFICE.

JOSEPH J. HIGGINS, OF SILVER CREEK, PENNSYLVANIA.

EXCAVATING-BUCKET.

1,106,146.

Specification of Letters Patent.

Patented Aug. 4, 1914.

Application filed October 15, 1913. Serial No. 795,288.

To all whom it may concern:

Be it known that I, JOSEPH J. HIGGINS, a citizen of the United States, and a resident of Silver Creek, in the county of 5 Schuylkill and State of Pennsylvania, have made certain new and useful Improvements in Excavating-Buckets, of which the following is a specification.

My invention relates to improvements in 10 excavating buckets and it consists in the combinations, constructions, and arrangements herein described and claimed.

An object of my invention is to provide 15 a bucket having means for suspending the same which may be readily attached to or detached from the bucket in a minimum time.

A further object of my invention is to 20 provide a bucket having suspending means which are less liable to be broken than the ordinary bolts.

Other objects and advantages will appear 25 in the following specification and the novel features of the device will be particularly pointed out in the appended claim.

My invention is illustrated in the accompanying drawings forming part of this application in which—

Figure 1 is a perspective view of the 30 bucket showing the attaching means, and Fig. 2 is a plan view of the bucket.

In carrying out my invention I make use 35 of a bucket of any shape, but preferably of that shape shown in Fig. 1. It will be understood that this bucket is to be used in connection with an elevator for elevating coal or other minerals from mines.

The elevator buckets now in common use 40 have an attachment which is made by a bolt inserted in holes in the body portion of the bucket with a nut on the inside of the bucket for holding the bolts. These bolts break frequently due to heavy weights imposed on the elevator and require con- 45 siderable delay and expense in making re- pairs. The device which forms the subject of the present invention is designed to prevent delay in making repairs and also to 50 avoid the frequency of breaks.

The bucket consists of a body portion 1 having sloping sides and end portions 2, 55 which are secured to the body portion by means of rivets or in any other suitable manner. This forms a V-shaped receptacle as shown.

The attachments for holding the bucket consist of a link 3 having loops 3^x at its ends. The link is provided with a pair of arms such as those shown at 4 and 5. The arm 4 is bent laterally at 4^a, thence 60 inwardly at 4^b, passing through an opening 6 in the end 2, is bent laterally at 4^c again and lies close to the side of the end member 2 of the bucket. The arm 5 is bent laterally in the opposite direction at 5^a and is 65 bent at 5^b, the arm passing through one of the openings 6, being bent laterally again at 5^c and being brought up close against the side of the end member 2. The attachment on the opposite end is similarly se- 70 cured to the end member 2 of the bucket.

From the foregoing description of the various parts of the device the operation thereof may be readily understood.

The links 3 having loops 3^x at each end 75 are provided with the arms 4 and 5 which are bent laterally at 4^a and 5^a and 4^b and 5^b. The ends of the arms 4 and 5 are inserted through the openings 6 and are then bent at 4^c and 5^c outwardly against the inner wall 80 of the end member 2. The other attachment is similarly secured.

It will be noted that the slots 6 in the ends 2 are elongated. This provides for arms 4 of considerable width with respect 85 to their thickness so that when they are bent in the manner described they present a thick portion of metal which must be sheared off if the attachment is broken from the bucket. This rarely occurs, since, as stated, in order to break the device off it must be broken clear across the width of 90 the strips 4 and 5. If, however, one of these devices is broken the ends are bent inwardly and the device is immediately withdrawn, 95 a new attachment being placed in position and the ends being bent so as to lie close against the inside of the end members 2.

It will be observed that the portions of 100 the arms between the bends 4^a, 4^b and 5^a, 5^b respectively form abutments to prevent the inward movement of the attachment, while the bent ends of the attachment on the inner sides of the wall prevent the outer move- 105 ment. There is therefore no play inwardly and outwardly through the openings 6.

I claim:

In an elevator bucket, a body portion, 110 end portions secured thereto and provided with vertically extending elongated slots,

vertically extending links having loops at their ends, a pair of arms secured to said links at their central portions, said arms being bent laterally, a portion of said arms

5 being arranged to abut the outer side of the end portions, the ends of said arms being bent inwardly and arranged to extend

through said openings and being bent back upon themselves to lie close to the inner sides of said end portions.

JOSEPH J. HIGGINS.
